(57) CLAIM

The ornamental design for a boot, as shown and described.

DESCRIPTION

FIG. 1 is a perspective view of the first embodiment of a boot showing my new design.

FIG. 2 is a right-side perspective view thereof.

FIG. 3 is a left-side perspective view thereof.

FIG. 4 is a front perspective view thereof.

FIG. 5 is a rear perspective view thereof.

FIG. 6 is a top perspective view thereof; and,

FIG. 7 is a bottom perspective view thereof.

The broken lines in the drawings represent portions of the boot that form no part of the claim.
